UNITED STATES PATENT OFFICE

2,474,051

ENDLESS BELT GRADER

Bernis W. Hatch, Atlanta, N. Y.

Application April 29, 1946, Serial No. 665,709

4 Claims. (Cl. 209—307)

1

This invention relates to belts made of a series of pivotally connected bent wire strands or links shaped to provide openings between the links of predetermined size, for retaining vegetables, fruits or like articles of larger size, while permitting such articles of smaller size to drop through the openings and thus separate or grade the articles according to size, such belts being disclosed, for example, in the prior patents to Boggs, No. 1,032,375, and Ghent, No. 1,899,437.

In such prior belts the wire strands or links have been in the shape substantially of flattened spirals so that the coils of each link can be looped through the coils of adjacent links by rotating each link and so threading it through the loops of an adjacent link. In this construction, however, each link has the shape of a spiral of the same hand, either right or left, from one margin of the belt to the other, with the result that the lower portions of the coils of each link have been aligned with the similar portions of adjacent links obliquely across the width of the belt, thus forming aligned depressions or valleys which have tended to direct the products fed to the belt toward one side thereof so as to interfere with the uniform distribution of the articles over the belt surface as desired for most uniform and efficient sizing operations.

One object of the present invention is to provide a belt of the above character having an improved construction and mode of operation for overcoming the above described defect.

Another object is to provide an improved grader belt so constructed as to gradually direct the articles to be graded, away from both margins and toward the center of the belt, so as to maintain a more even distribution of the articles for a more efficient sorting action of the belt thereon.

To these and other ends the invention resides in certain improvements and combinations of parts, all as will be hereinafter more fully described, the novel features being pointed out in the claims at the end of the specification.

In the drawings:

Fig. 1 is a side elevation of a simple form of grading machine having a grader belt embodying the present invention;

Fig. 2 is an enlarged plan view, partly broken away, of a link belt embodying the present invention;

Fig. 3 is an enlarged, fragmentary detail of a portion of the belt shown in Fig. 2, and

Fig. 4 is a view similar to Fig. 3, but showing a slightly modified form.

2

The present invention provides an endless wire link belt indicated generally at 10 (Fig. 1), for passing around angular rolls, as 11, of a grading machine, one of such rolls being preferably provided with a hand crank or power means (not shown) for rotating it to drive the belt. The potatoes or other articles to be graded are fed through a hopper 12 onto the flat upper reach 13 of the belt, the articles of smaller size dropping through the belt openings to suitable collecting and discharge means (not shown) and the larger articles being delivered through a discharge chute 14 into a bag or other receptacle 15. Such grading machines, one of which is disclosed in the above Patent No. 1,032,375, are well known in the art and form no part of the present invention.

In the preferred embodiment herein disclosed by way of illustration, each link 16 is made of a length of relatively stiff wire bent into the shape, 20 substantially, of a flattened spiral adapted to have its coils pivotally looped through the coils of an adjacent strand by rotating the link and so threading it through the coils of the adjacent link. Thus link 16 (Fig. 2) has its coil 17 passing over, 25 around and under the coil 18 of an adjacent link and thence looped through the coil portion 19 of the link on its opposite side and thence again looped over, around and under the coil portion 20 of the first link and so on. By means of this construction the adjacent links are pivotally inter-looped with each other and the coils form with adjacent links a series of openings 21, of predetermined size, through which articles of smaller size are allowed to drop so as to separate them 35 from the larger articles retained on the belt. It will be noted that the interlooped coil portions 17 are arranged substantially in planes normal to the general surface of the belt while the inter-looped coil portions 23 have a substantially semi-circular curvature lying substantially in the plane 40 of the belt and that the article receiving openings 21 have substantially equal width longitudinally and transversely of the belt so as to permit the passage therethrough of articles whose maximum 45 diameter is less than that of the width of the opening. By means of this construction, furthermore, the wire has a shape into which it may be readily bent on a machine such as disclosed in said Patent No. 1,899,437, and then assembled 50 with other links by rotating and threading the coils of one through those of another as described.

It will be seen in the above construction that the lower portions, as 22, 23 and 24, of the coils of successive links tend to form a series of depressions, channels or valleys, aligned obliquely in-

wardly and rearwardly of the direction of travel of the belt, as indicated by the arrow 25. If the spiral shape of each link is allowed to extend uniformly from one margin to the other of the belt, as in the prior art belts, the articles fed to and rolling on the surface of the moving belt tend to follow such valleys so as to be moved toward and fall off one side of the belt or to collect at one side and thus interfere with uniform distribution over the belt and efficient sorting action.

It has been proposed to overcome this difficulty in various ways, as by providing a retaining flange along the side of the belt to prevent the articles from dropping off, but such provisions have provided only partial remedies without affording a satisfactory solution of the difficulty.

I have found that this defect may be satisfactorily overcome by forming each link of at least two sections, 26 and 27, aligned with each other transversely of the belt and having their coils arranged in spirals of opposite hand, respectively. Thus, section 26 is in the form, substantially, of a left hand spiral, while section 27 is in the form of a right hand spiral, with the result that the coils of the sections are so arranged that the valleys extend from both margins of the belt obliquely inwardly and rearwardly of the direction of travel of the belt, as indicated by the arrows, 28 and 29, respectively. By means of such an arrangement the articles are gradually directed away from both margins and toward the center of the belt, where any excessive concentration or crowding of the articles is self-correcting by outward rolling of the articles so as to maintain, by these counter-acting tendencies, a fairly uniform distribution of the articles and efficient grading action of the belt.

Fig. 3 shows on an enlarged scale the overlapping arrangement of the inner ends of a pair of links 26 and 27, the end 31 of link 26 being crossed under the end 30 of link 27. Fig. 4 shows an alternative arrangement in which the link 26 has the same construction but an aligned link 33 has its end 34 crossed under the end 31 of link 26.

As in the case of the prior art belt, the links are readily formed by machines such as disclosed in said Patent No. 1,899,437, arranged to form spirals of right and left hand shape, respectively, and the spiral link sections are easily and quickly turned and threaded into looping engagement with adjacent spiral sections of like hand, respectively, in an adjacent link, so that the belt may be economically manufactured and assembled as before.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A belt for grading fruit and vegetable products and like articles according to size comprising a series of transversely extending wire links each having pivotal engagement with adjacent links at transversely spaced points and being shaped to provide article receiving openings therebetween intermediate said points of engagement, said openings having substantially equal width longitudinally and transversely of the belt and said links being shaped to provide a series of valleys spaced longitudinally of said belt and inclined

obliquely inwardly and rearwardly of the direction of travel of the belt, from both margins toward the center thereof, to distribute the movement of the articles fed onto said belt from the margins toward the center thereof.

2. A belt for grading fruit and vegetable products and like articles according to size, comprising a series of transversely extending wire links each being coiled in substantially spiral shape with its coils looped pivotally through the coils of adjacent links and providing article receiving openings therebetween, said openings having substantially equal width longitudinally and transversely of the belt and having opposite sides extending substantially parallel with the longitudinal extent of the belt and the coils of successive links being arranged in echelon to provide a series of valleys inclined obliquely inwardly and rearwardly of the direction of travel of the belt, from both margins toward the center thereof, to distribute the movement of the articles fed onto said belt from the margins toward the center thereof.

3. A belt for grading fruit and vegetable products and like articles according to size comprising a series of longitudinally spaced, transversely extending wire links pivotally connected with each other, each of said links comprising a plurality of transversely aligned sections each having coils of substantially flat, spiral shape, the coils of adjacent sections in each link having right and left hand spiral shapes, respectively, said coils being looped through the coils of sections of adjacent links and shaped to provide article receiving openings therebetween, said openings having equal width longitudinally and transversely of the belt and having opposite sides extending substantially parallel with the longitudinal extent of the belt and said coils having depressed portions forming valleys extending obliquely inwardly and rearwardly of the direction of travel of the belt, from both margins toward the center thereof, to distribute the movement of articles fed onto said belt from the margins toward the center thereof.

4. A belt for grading fruit and vegetable products and like articles according to size comprising a series of longitudinally spaced, transversely extending wire links pivotally connected with each other, each of said links comprising a plurality of transversely aligned sections each having coils of substantially flat, spiral shape, the coils of adjacent sections in each link having right and left hand spiral shapes, respectively, said coils being looped through the coils of sections of adjacent links and shaped to provide article receiving openings therebetween, said openings having substantially equal width longitudinally and transversely of the belt and having opposite sides extending substantially parallel with the longitudinal extent of the belt, said interlooped coil portions along one side of each link section being arranged in planes substantially normal to the general plane of the belt and the interlooped coil portions along the other side of each link section having substantially semi-circular curvature lying substantially in the general plane of the belt and said coils having depressed portions forming valleys extending obliquely inwardly and rearwardly of the directions of travel of the belt, from both margins toward the center thereof, to distribute the movement of articles fed onto said belt from the margins toward the center thereof.
